UNITED STATES PATENT OFFICE.

WINFIELD S. LAWS, OF CUSHING, OKLAHOMA, ASSIGNOR, BY DIRECT AND MESNE ASSIGNMENTS, OF SEVEN-SIXTEENTHS TO MILTON T. WILLIAMS AND TWO-SIXTEENTHS TO MILO ORLANDO CANNADA, BOTH OF CUSHING, OKLAHOMA.

OIL-WELL DRILL.

1,174,741.

Specification of Letters Patent.

Patented Mar. 7, 1916.

Application filed October 9, 1914, Serial No. 865,822. Renewed February 1, 1916. Serial No. 75,623.

To all whom it may concern:

Be it known that I, WINFIELD S. LAWS, a citizen of the United States, residing at Cushing, in the county of Payne and State 5 of Oklahoma, have invented certain new and useful Improvements in Oil-Well Drills, of which the following is a specification.

This invention relates to oil well boring 10 drills.

One of the principal objects of the invention is to provide a drill as set forth with means for preventing the drill bit from loosening in the well, said means 15 adapted to act as a core or lock whereby the drill stem and jar may be raised from the well should they become broken.

Another object of the invention is to provide a well boring drill with a core or lock 20 in the form of a cable or rod, connected at its lower end to the drill bit and at its upper end having a loose connection with the drill jar, means being provided for locking the cable or rod against rotation relatively to 25 the jar whereby to prevent loosening of the bit.

A further object of the invention is to provide a device of the class described which will be simple, durable, efficient in 30 operation and inexpensive to manufacture.

With these and other objects in view which will become apparent as the description proceeds, the invention resides in the construction, combination and arrangement 35 of parts, hereinafter more fully described and claimed, and illustrated in the accompanying drawing, in which like characters of reference indicate like parts throughout the several figures, of which—

40 Figure 1 represents a longitudinal central sectional view of a drill constructed according to my invention. Fig. 2 represents a detail perspective view of the upper portion of the drill jar. Fig. 3 represents a central sectional view thereof. Fig. 4 represents a perspective view of the cover plates or doors in separated position. Fig. 5 represents a side elevational view of the upper portion of the lock or core, and Fig. 50 6 represents a detail central sectional view of the lower portion of the drill showing the connection of the drill stem and bit.

Referring more particularly to the drawing 5 indicates the drill stem, which is hol-

low, and 6 indicates the drill bit. The latter is threaded at its upper end at 7 for the reception of the lower end of an interiorly left hand threaded sleeve 8. The upper end of sleeve 8 screws onto the left hand exteriorly threaded portion 9 at the lower end 60 of stem 5. The bit is provided with an axial right hand threaded lug 10 which screws into a socket 11 at the lower end of the stem.

The core or lock is indicated at 12, and 65 may be in the form of a rod or suitable cable. The core includes an upper section 13 which is flattened, a central section 14, and a lower section 15. The upper and lower sections are preferably in the form 70 of metallic rods, while the central section 14 may be either in the form of a rod or cable. The lower section 15 of the core or lock extends axially of the drill bit 6 and projects above the upper end of the latter, 75 and at its lower end is anchored and rabbed in the bit as at 16. The upper end of section 15 extends through lug 10 and socket 11 and into a socket 17 at the lower end of central section 14. A counter-sunk 80 screw 18 is adapted to be passed through registering openings in socket 17 and upper end of section 15 for securing the central and lower sections together. A similar arrangement may be utilized in connecting 85 the upper and central sections.

A hollow coupling 19 is threaded onto the upper end of the drill stem and the drill jar 20 is adapted to reciprocate at its lower end within the coupling for imparting the 90 desired movement to the drill. Said coupling is provided with longitudinal slots 21 to allow the escape of water whereby the movements of the jar will not be retarded. The core or lock extends upwardly through 95 the stem and the coupling and the jar.

Jar 20 is provided at its upper end, with a larger loop 22, to which the motive power is suitably connected in any well known manner. A pair of circular door plates or 100 covers 23 and 24 of which the former is the upper and the latter the lower respectively, are hingedly connected each to one arm of loop 22 by means of a staple 25 in the manner indicated in Fig. 2. The diameter of the cover plates is substantially equal to that of the drill jar, and said plates are adapted to be swung upon the arms of loop 105

22 whereby to either dispose them in the relative position shown in Fig. 2 or to swing them outwardly from the top of the jar. As indicated the cover plates are each pivoted 5 with a slot 26 extending in a radial direction from the periphery to a point slightly beyond the center of the plate. The slots when the plates are in relative position indicated in Figs. 2 and 4 extend in opposite 10 directions, and said slots are adapted to embrace the flattened or squared portion or member 13 of the core or lock, when the plates are in the position shown in Figs. 2 and 3, whereby to prevent rotation of the 15 core or lock relatively to the drill. The upper plate is provided with diametrically opposed upwardly extending lugs 27, one of which is positioned adjacent the staple 25 carried by said plate, and the lower plate 24 is also provided with a similar pair of lugs 28. Plate 23 adjacent lugs 27 is slotted as at 29, and through these slots the lugs 28 may be projected when the plates are being disposed in locked position. Lugs 27 and 25 28 are provided with openings 30 adapted to be brought into registration with each other whereby wires or similar keys 31 may be passed through the openings for maintaining the covers in locked position.

30 Near the upper end of section 13 of the core or lock, a cross bar or stop 32 is carried, and when the cover plates are in locked position extends across the uppermost of said plates. A smaller loop 33 is carried 35 by the cross bar or stop 32, and is disposed within loop 22. The relative lengths of the loops is such that reciprocation of the drill jar will not cause the engagement or the interference of one of the loops with the other. In disposing the cover plates in the 40 position shown in Fig. 2 the jar is lowered relatively to the core or the core is raised relatively to the jar so that cross bar 32 will be in spaced relation with the cover plates, 45 and the lowermost plate is then swung across to cover the jar, the slot in the lower plate traveling over the squared portion of the core during this operation. The upper plate is then swung across and is lowered upon 50 the lower plate so that the slots 29 pass over lugs 28 carried by said lower plate, and the keys or wires may then be put in place.

Should any of the portions or parts of the drill break or become disabled during 55 the operation of the drill, the loop 33 will serve as means by which the tools may be recovered and withdrawn from the well. The engagement of the squared portion of the core in the slots provided in the cover 60 plates, will prevent rotary movement of the bit relatively to the core, thus insuring the bodily rotation of the core and bit during the operation of drilling the well. The device will serve to lock the stem, bit and jar 65 against relative rotation, thus reducing to a

minimum the danger of loss of the drill bit from the stem and also acts as a means by which any of the string of tools which might become broken may be bodily lifted from the well without danger of loss of any of the 70 tools from the string.

The device is simple in construction and may be quickly attached and detached.

Although I have described the preferred embodiment of my invention, I may desire 75 to make such changes in the construction, combination and arrangement of parts thereof as do not depart from the spirit of the invention and the scope of the appended claims.

80

I claim:—

1. The combination with a drill stem, of a drill bit detachably connected thereto, and a drill jar for the stem, of a core secured to said bit against rotary movement 85 relatively thereto, said core extending through said stem and jar, and having a squared portion disposed within the jar, a pair of doors hingedly connected to said jar at the upper end thereof and adapted to fold over the jar one above the other, said doors provided with oppositely disposed slots adapted to engage over the squared portion of the core to prevent relative rotation of said jar and core, a stop provided 95 on said core above the doors, a loop provided on the stop, a larger loop provided on the jar within which said first loop is adapted to be disposed, and means for locking the doors together.

100

2. The combination with a drill stem, a drill bit removably secured thereto and a jar for the stem, of a core secured to said bit against rotation relatively thereto, said core extending through said stem and jar 105 and being provided with a flattened portion, a pair of doors hingedly connected to said jar and adapted to fold over the upper end thereof one above the other, said doors provided with oppositely extending slots 110 adapted to engage over the flattened portion of the core for preventing relative rotary movement of the jar and core, means provided on the core above the doors for limiting the movement of the jar relative 115 to the core, and means provided on said core whereby the latter may be engaged for withdrawing the drill parts from a well.

120

3. The combination with a drill stem, a bit removably secured thereto and a jar for 120 the stem, of a core connected to said bit against rotation relatively thereto, said core extending through said stem and jar, cooperating means between the jar and core adapted to prevent relative rotary movement of them, and adapted to allow longitudinal movement of the jar and core relatively to each other, stop means carried by the core and adapted to limit relative longitudinal movement of the jar and core, 130

and means carried by the core whereby the same may be engaged by a lifting element.

4. The combination with a drill stem, a bit removably secured thereto, and a jar for the stem, of a core connected to the bit against rotary movement relatively thereto, and interlocking means between the jar and core adapted to prevent rotary relative movement of the same, and adapted to allow longitudinal movement of the same, substantially as described.

5. The combination of a drill stem, a bit removably secured thereto, a jar for the stem, a core connected to the bit against rotary movement relatively thereto, said core extending through said stem and jar and having a flattened portion, means carried by the jar and adapted to engage the flattened portion of the core to prevent rotary movement of the jar relatively to the core, and adapted to allow longitudinal movement of the jar relatively to the core, in one direction.

6. The combination with a drill stem, a bit removably secured thereto and a jar for the stem, of means for locking said jar and bit against relative rotary movement, said means adapted to allow longitudinal movement of the jar relative to the stem.

7. A device of the class described including a drill jar, and a core, and means for locking said jar against rotation relatively to the core, said means comprising a pair of hinged plates adapted to be disposed

over said jar one above the other, said plates and core provided with co-acting engaging means whereby to prevent rotary movement of the plates relatively to the core, and adapted to allow longitudinal movement of the plates relatively to the core, and means for locking the plates together.

8. A device of the class described including a drill jar and a core disposed therein, said core having a drill bit connected therewith, coöperating means between the jar and core adapted to prevent rotary movement of the jar and core relatively to each other and adapted to allow longitudinal movement of them relatively to each other, and means carried by the core adapted to limit the movement of the jar and core in one direction.

9. A device of the class described including a drill jar, a core disposed therein, said core having a drill bit associated therewith, coöperating means between the jar and core for allowing of relatively longitudinal movement of them and for preventing relative rotary movement of them, means for limiting the relatively longitudinal movement in one direction, and means adapted to allow the engagement of a lifting element with the core.
